DESIGN FOR A DRESS

Irene Zerner, New York, N. Y.

Application September 12, 1940, Serial No. 94,978

Term of patent 3½ years

To all whom it may concern:

Be it known that I, Irene Zerner, a citizen of the United States of America, residing in the city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

Fig. 3 is an enlarged fragmentary view of the

dress shown in Fig. 1 illustrating one of the pocket members in detail.

The characteristic feature of my design resides in the combination on the specific dress disclosed of the specific embroidered trim on the double pocket arrangement on the blouse portion in association with the stitched pleated skirt, all as shown.

I claim:

The ornamental design for a dress, substantially as shown and described.

IRENE ZERNER.
